UNITED STATES PATENT OFFICE.

AUGUSTUS D. CURTIS, OF CHICAGO, ILLINOIS, ASSIGNOR TO NATIONAL X-RAY
REFLECTOR CO., OF CHICAGO, ILLINOIS, A CORPORATION OF ILLINOIS.

LIGHTING-FIXTURE.

1,295,705.

Specification of Letters Patent.

Patented Feb. 25, 1919.

Application filed June 20, 1917. Serial No. 175,780.

To all whom it may concern:

Be it known that I, AUGUSTUS D. CURTIS, a citizen of the United States, residing at Chicago, in the county of Cook and State 5 of Illinois, have invented a certain new and useful Improvement in Lighting-Fixtures, of which the following is a specification.

My invention relates to that class of fixtures, called luminous bowl fixtures, such as 10 are described in Patent #1,121,196 issued to Earle C. McKinnie, and is an improvement thereon. In the patent referred to, a glass diffusing cup is provided and its bottom wall is thickened to prevent the intense spot light 15 from the electric light bulb directly below the fixture. This thickened portion is also expected to reflect the rays and thus assists in diffusing the light to the luminous bowl.

My invention has for its object to provide 20 a special reflector or reflecting surface, which will be much more efficient in illuminating the luminous bowl.

My means of accomplishing the foregoing objects may be more readily understood by 25 having reference to the accompanying drawings, which are hereunto annexed and are a part of this specification, in which:

Figure 1 is a vertical sectional view of a fixture provided with my improvement.

Fig. 2 is a detail view of the reflector.

Similar reference numerals refer to similar parts throughout the entire description.

As shown in the drawings, the fixture 5 is suspended by chains 3, secured to the usual 35 ceiling canopy 4. In the center of the fixture 5, is mounted a reflector 6, adapted to direct the light rays from the electric light bulb 7, upwardly and outwardly. In the bottom of the reflector 6, is mounted the diffusing cup 8, which is preferably made of 40 semitranslucent glass. Within the diffusing

cup 8, I place my reflector 9, made of opaque material having a mirrored or other reflecting surface, the reflector being either in the form of a cone or a pyramid. As it is 45 formed of opaque material, it follows that the spot light is eliminated, while the angle of the reflector 9, is such that the light rays are reflected through the walls of the diffusing cup 8, so that the luminous bowl 10, 50 which is secured to the fixture 5, and surrounds the reflector 6, and the diffusing cup 8, is evenly illuminated and there is a complete absence of any spotted effect thereon, and it furnishes a mellow, even glow, producing a very satisfactory illumination. 55

Although I have described the reflector 9, as being formed separately from the diffusing cup 8, it will be apparent to persons skilled in the art, that it may be made integral with the diffusing cup without departing from the spirit of my invention, which is designed to furnish means to deflect and reflect the light rays through the side walls 60 of the diffusing cup 8. 65

Having described my invention what I regard as new and desire to secure by Letters Patent is:

The combination in a fixture of an electric light bulb with a reflector to direct the light 70 rays upwardly and outwardly, a diffusing cup mounted in the bottom of said reflector, a glass bowl secured to the fixture and surrounding the reflector and diffusing cup, 75 and a conoidal reflector within said diffusing cup and adapted to reflect the light rays through the side walls of said cup to cause the glass bowl to be illuminated.

In testimony whereof, I have signed the foregoing specification.

AUGUSTUS D. CURTIS.
